UNITED STATES PATENT OFFICE.

GEORGE MILLER, OF BALTIMORE, MARYLAND.

DESIGN FOR A BOX.

SPECIFICATION forming part of Design No. 26,314, dated November 24, 1896.

Application filed October 17, 1896. Serial No. 609,250. Term of patent 14 years.

To all whom it may concern:

Be it known that I, GEORGE MILLER, a citizen of the United States, residing in the city of Baltimore, in the State of Maryland, have 5 invented and produced a new and original Design for Boxes, of which the following is a specification, reference being had to the accompanying drawings, forming part thereof.

In the accompanying drawings, Figure 1 is 10 a view in elevation, and Fig. 2 is a vertical sectional view illustrating my design.

The leading feature consists in the bevel formation at the lower edge or angle of the box where the side joins the bottom.

15 A represents the box; 1, the bottom; 2, the side; 3, the cover, and 4 is the bevel or diag-

onal lower edge. This bevel or diagonal formation really divides the usual angle of ninety degrees into two of forty-five degrees, with the object in view of facilitating the removal of 20 the contents of the box, a portion of which so commonly adheres in the corner in consequence of the sharp angle and the attendant difficulty of insertion of the finger or other means for removing the contents. 25

What I claim is—

The design for boxes herein shown and described.

GEORGE MILLER.
